SCIENTIFIC DEMONSTRATION TOY

Charles W. Sherburne, 3409 S. Patton Ave.,
San Pedro, Calif. 90731

Filed Nov. 12, 1965, Ser. No. 88,071

Term of patent 14 years

(Cl. D25—1)

FIG. 3

FIG. 6

FIG. 2

FIG. 4

FIG. 5

FIG. 1 is a top plan view of a scientific demonstration toy showing my new design;

FIG. 2 is a front side elevational view thereof, the rear side elevational view thereof being identical is omitted for brevity;

FIG. 3 is a right end elevational view thereof, the left end elevational view thereof being identical is omitted for brevity;

FIG. 4 is a bottom plan view thereof;

FIG. 5 is a side elevational view of the scientific demonstration toy in FIG. 1 wherein the spheres that are integral thereon have been omitted; and

FIG. 6 is a right end elevational view of the embodiment of FIG. 5, the left end elevational view being identical is omitted for brevity.

I claim:

The ornamental design for a scientific demonstration toy, substantially as shown and described.
